20 Claims. (Cl. 34—35)

1

This invention relates to the disposal of waste products and more particularly to the enameling oven art.

In the enameling of articles, and especially magnet wire, the article or wire is passed through an enamel bath and from thence into the baking chamber. The volatile content of the enamel which is carried by the article from the bath into the chamber is given off in the form of a fume or vapor which, when discharged into the outside atmosphere, is objectionable and becomes a nuisance to the neighborhood as well as to the personnel of the enameling plant itself. Impractical attempts have been made to dispose of the fume, as by absorbing the same in water or solvents, or by burning the same with additional fuel at an enormous expense.

The primary object of the present invention is to provide an improved method of and apparatus for disposing of the obnoxious fume from enameling ovens economically and in a practical and satisfactory manner whereby utmost efficiency is secured in plant operation and fume removal and burning. Further the invention has for its object the disposal of the fume in a manner advantageous to the enameling process.

The foregoing and other objects will manifest themselves as the following description progresses, reference being had to the accompanying drawing wherein:

Fig. 1 is a vertical sectional view of the improved enameling oven or furnace taken about on line I—I of Fig. 2 and by which the improved method may be practiced;

Fig. 2 is a rear elevation of the enameling oven, partly in section, taken about on line II—II of Fig. 1;

Fig. 3 is a view of the oven in horizontal cross section as viewed about on line III—III of Fig. 1;

Fig. 4 is a slightly enlarged view in vertical cross section through one of the combustion chambers, taken about on line IV—IV of Fig. 3;

Fig. 5 is a vertical longitudinal section through the combustion chamber taken about on line V—V of Fig. 4;

Fig. 6 is an end elevation, in fragment, of the enameling oven;

Fig. 7 is a horizontal sectional view about on line 7—7 of Fig. 8 showing a modified enameling oven;

Fig. 8 is a fragmentary vertical sectional view through such modified oven construction about on line 8—8 of Fig. 7;

Fig. 9 is a transverse vertical sectional view taken about on line IX—IX of Fig. 7;

2

Fig. 10 is a view similar to Fig. 7, but showing a further modification as viewed about on line 10—10 of Fig. 11;

Fig. 11 is a vertical section on the modified enameling oven shown in Fig. 10 as viewed about on line 11—11 therein;

Fig. 12 is a fragmentary vertical transverse sectional view taken about on line XII—XII of Fig. 11;

10 Fig. 13 is a vertical sectional view of an enameling chamber heated by gas burners; and

Fig. 14 is a diagrammatic view showing a further embodiment of the present invention.

Referring more particularly to the drawing, 15 the enameling chamber 1 is suitably insulated, as indicated at 2. The chamber may be disposed either vertically or horizontally, and the baking heat is furnished through a fuel burning process from which the highly heated products of

20 combustion pass into the chamber where they may directly contact the coated article, or they may be confined against commingling with the enameling fume. Where the heated gases are confined one or more heating elements 3 may be provided. In Fig. 1, two such heating elements

25 are shown. The wire 4 to be coated passes between such heaters after leaving the enamel bath 5. One end of the enameling chamber is closed by a wall 6, having a wire slot-like entrance 7 through which the several strands of wire move, while the opposite end of the chamber is closed by a wall 8 which has a wire exit in the form of a slot 9. The slot 7 is of sufficient size to admit the necessary amount of air for diluting and thereby rendering the volatile matter or fume

30 safe from explosion. This is a precautionary measure if not a legal requirement. The exit slot permits the escape of the air-diluted fume stream from the chamber into a hood 10 usually under its own heat head. Where the enameling oven is horizontal, the heat head may include an assisting fan. The fume is drawn off from the hood 10 under a very light urge by a fan 11.

35 Where wire is the object to be enameled, it is suitably supported in its travel through the enameling chamber by rolls 12 and 13 onto which it passes from a suitable source of supply and an intermediate booster drum 14, additional 40 rollers 15 serving to guide the wire strands outside the chamber, all in the customary manner for maintaining the proper tension on the wire.

45 The enameling process requires very accurate and consistent heat control for evaporating the 50 solvent in the enamel coating and baking the 55

latter on the wire. Heretofore the enamel fume has discharged into the outside atmosphere. The temperature of the discharging fume may approximate 700° F., or thereabouts. Therefore, in addition to the obnoxious fume nuisance, a considerable waste of heat energy or B. t. u. has been made. With the present invention this heretofore wasted B. t. u. and latent heat are conserved for burning the enamel fume in the combustion chamber of the enameling oven or furnace. One or more combustion chambers may be employed. In the embodiment of Fig. 1 two combustion chambers 16 have been illustrated, each provided with a burner or nozzle 17 and forming a part of a confined space 18 into which the enamel fume flows from the hood 10. A larger confined space may accommodate plural burners. After the fume is burned the gaseous products of combustion pass out through a drum extension 19 of the combustion chamber. The combustion chamber 16, 19, which starts at the delivery end of the nozzle, therefore constitutes a part of the confined space. The hot gases will flow upwardly through a bottom opening 20 of a heater 3 and finally out through stack 21 into the atmosphere. Thus the bottom opening or communication 20 constitutes a means for furnishing heat to the lowermost portion of the heating element 3 and thereby concentrates the heat close to the entranceway for prompt action upon the freshly coated wire as it enters the baking or enameling chamber. The peak of the heat curve within the enameling chamber is thereby located adjacent the entrance with the result that the baking process is accelerated, the wire may be moved faster through the chamber in the presence of this increased heat, and a saving of fuel is accomplished over the heretofore practice of injecting heat well up in the chamber toward the slot 9 which now becomes largely unnecessary. Furthermore, the location of the drum 19 beneath its heater and within the enameling chamber will augment the supply of heat close to the entranceway 7.

As the fume and air mixture is drawn from the hood 10 by the fan 11 it is conducted by a conduit 22 over into the entranceway 23 of the confined space 18 where it may be deflected by a baffle 24, Fig. 4, to a location well to the rear of the delivery end of the burner 17 for proper translatory flow into the combustion chamber through the throat 25. In practice, the conduit 22, the fan 11, and the hood 10 will be thoroughly insulated (not shown herein for the sake of clearness) to maintain the hot fume temperature against cooling sufficiently to condense upon the adjacent wall.

Within the combustion chamber complete combustion of the burner-supplied fuel as well as a thorough burning of the fume occurs. Additional air must be admitted in volume sufficient to supply the required oxygen over and above the fume-diluting and oxygen supplying air admitted through the slot 7. Preferably, this additional oxygen is admitted from the room atmosphere through a slot 26 in the top of the hood. The capacity of the slot is regulated to guard against cooling the fume stream to a vapor condensing degree. Such control is effected by a valve 27 which is vertically adjustable on a bracket 28 by any suitable means. The valve will be fixed in a given adjustment by set screws 28' and may be streamlined in shape, as at 29, to deflect and direct the inflowing air. The adjacent underlying surface 30 also may be streamlined so as to deflect

a part of the fume stream, after it enters the hood under its heat head velocity from the enameling chamber, for inducing or effecting the inflow of air through the opening 26. This will serve to prevent the escape of fume from the hood through the slot 26 into the room atmosphere.

In addition to the fume deflection aforesaid there is provided within the hood a vane or surface 30' which extends from the exit fume slot 9 with an upwardly streamlined curve whereby another part of the fume under its heat head velocity will follow such vane surface contour and thereby direct the stream of fume and extra air toward the discharge end of the vane. This vane or surface 30' may be adjustably fixed by a suspending hanger 30''. It will be noted that this fume stream emanating from the slot 9 is under its own heat head and consequently the enameling oven temperature is maintained at an efficient degree. To insure this efficiency, the force of the fan is preferably not impressed upon the fume stream adjacent the slot 9, but rather toward the outer or discharge end of the surface 30' and this is facilitated by providing the large intermediate chamber. By adjusting the hanger 30'' the space above the discharge end of the surface may be varied and consequently the suction influence of the fan upon the fume stream and air mixture within the hood may be varied to pull in more or less air through the opening 26 without interference, or substantial interference, to the natural flow of the fume from the slot 9 under its own heat head. The force of the fan is regulated by a damper 31 placed in the suction side thereof for pulling the fume and extra air away from the hood. The delivery of the fan to the respective confined spaces 18 may be regulated by individual dampers 31'. The oven operator may readily determine the condition of the flame through a peep hole 33 and accordingly adjust one or more of the several dampers. All excess air above theoretical air may thereby be excluded with a consequential saving in fuel. The capacity of the air slot 26, through which the enameled wire strands emerge from the hood, will be determined according to the gauge of the wire to be processed. A single adjustment of the valve 27 may serve a wide range of sizes of wire as may also a given setting of the vane 30'.

To burn enamel fume thoroughly requires intense heat; so much so that previous attempts to burn the fume have consumed such an increased volume of fuel as to render the procedure impractical and prohibitive because of the added cost. In contrast, the practice of the present invention enables the enameling process to be carried on, and a complete burning of the enamel fume effected, with a fuel consumption substantially less than that heretofore required to operate an enameling oven alone without any fume burning.

To accomplish this purpose in the present disclosure, the burner 17 is disposed off center and close to one wall or side of the throat 25 of the confined space, in a manner somewhat similar to the burner shown in my Patent No. 1,736,675. Along with this off-center displacement the burner nozzle is tilted slightly toward the wall to make the restricted induction effective in depressing the jet and flame toward the wall, in accordance with a well-known law, the issuing fuel jet and flame moving substantially parallel to the wall 32; being conformed thereto by the

pressure differential set up and without destructive impingement thereagainst. This surface-contour path of the flame is secured by inclining the burner nozzle gradually toward such wall until the jet and flame are attracted or depressed more or less thereupon. As the flame follows the contour of the wall and continues its movement into the combustion chamber it develops into a flattened tongue or layer upon the adjacent wall and thereby shields the wall surface from the cooling influence of the induced fume mixture which is freely induced elsewhere about the burner nozzle. The flame interposes itself between the relatively cooler fume mixture and the wall surface 32 to be heated, so that the wall will be more highly heated and this in turn will cause the flame to intensify its temperature with the result that the flame temperature will build itself up approximately or close to the theoretic flame temperature and sufficiently high to burn the fume content. A flame temperature is thereby insured to complete the burning of the fume as well as the fuel in the presence of the air content of the induced mixture. The additional volume of air admitted through the regulated opening 26 may be slightly in excess of that actually required both for burning the fume and for supporting the combustion of the fuel in the confined space or combustion chamber for slightly cooling or tempering off the high temperature of the products of combustion prior to their entry into the heating elements 3 to avoid injury thereto. By regulating the dampers or valves 31 and 31' the volume of additional air entering through the opening 26 may be varied so that the fan will draw in more or less additional air to secure and maintain the desired and proper proportion in the fume stream entering the hood 10 through the slot 9 without disturbing its natural heat head flow.

In practicing the method of the present invention, and in operating the embodiment disclosed in Figs. 1 through 6, the wire or object to be coated is passed through the enamel bath 5 and brought into the baking chamber through the entrance slot 7 where it is immediately acted upon by the intense heat provided by the admission of the products of combustion into the lowermost cavity portions of the heating elements 3. It is noted that these lowermost portions of the heating elements depend below the upper surface of the platform or oven-supporting frame members 34 and that the bottom connections 20 function to deliver the hot combustion products into the depending lower portions 3' of such heating elements. As previously stated, the delivery of the hot gases into the lower portions serve to concentrate the heat close to the entranceway within the baking chamber. A plotted graph of the heat curve in the combustion chamber, as compared to the former practice, will show the peak of the heat curve lowered substantially within the baking or enameling chamber, bringing it closer to the slot 7 and accelerating as well as expediting the enamel baking process. Consequently the wire may be run faster through the chamber. Further, it becomes unnecessary to supply additional heat higher up in the chamber.

The hot fume emanating from the chamber will flow out into the hood or compartment 10 and in transit therethrough intake other air through slot 29 before being drawn off by the fan and delivered to the confined space 18 where the fume particles and oxygen will be inducted

into the flame for consumption, while the superheated surface 32, which in extent reaches from a point immediately in front of the burner nozzle to a point substantially to the end of the flame, is protected against cooling contact with the fume and air mixture. The presence of the drum extensions 19 of the combustion chambers in the lowermost portion of the enameling chamber and on opposite sides of the entering wire strands, further insures the immediate application of a high baking temperature to the bath-coated object as it enters.

The supply of fuel to the burner may be regulated by a suitable control, such as a delicate pyrometer control indicated at 35, which control functions to open or close the control valve 36 in accordance with temperature conditions within the enameling or baking chamber 1. A bypass valve 37 may be maintained constantly opened to supply a prescribed minimum volume of fuel to the burner whenever the pyrometer controlled valve 36 is closed. The manipulation of the dampers 31' will call for a response by the pyrometer control and result in a modification of the fuel supplied the burner accordingly. Complete shut-off of the fuel can be effected by a service valve 38.

The induction of the fume stream mixture into the combustion chamber or confined space may be termed a restricted induction in that the induction is not uniform entirely about the axis of the fuel jet from the burner. The flame will lay itself upon the side wall 32 of the confined space and protect it from the cooling influence of the fume stream. Upon all other sides of the burning jet free induction will obtain by which the fume particles will be drawn into the flame and consumed in the presence of the fuel and the supplied air content. The high temperature developed by the restricted induction insures a completed combustion before the combustible products pass into the flues 20. Another reaction of this burning is that it keeps relatively superposed layers of high temperature flame and fuel in process of combustion between the surface 32 to be heated and the incoming fume stream. Therefore, the adjacent wall surface is brought nearer to the theoretical flame temperature with a resultant larger proportion of radiant heat, the fuel moving inwardly until combustion is completed. The fuel is laid in proximity to and moves substantially parallel to the surface to bring the flame temperature up to the fume burning intensity approximating the theoretical flame temperature. The radiant heat attendant to this intense heat of combustion will enter into the fume consuming process to aid in the elimination of any trace of fume from the products of combustion.

The burner nozzle 17 may be withdrawn a distance from the throat portion 25, as indicated at 17a, and a cooperating nozzle 17b arranged at an angle thereto so that their jets will converge to a point off center, or closer to one side of the confined space, with the result that fuel issuing from the angularly displaced nozzle 17b will deflect and spread the resultant flame from the contact point of convergence and toward the surface 32 which is to be heated. The burner nozzle in Fig. 3 is therefore compound in character. This flame deflection will serve to position the jet and flame at the correct angle of inclination, with respect to the side wall 32 where the jet velocity will cause the flame to adhere

close to the wall surface to obtain the advantages of the restricted induction as aforesaid.

The heaters 3 may be of any approved form. By way of illustration, and referring to Fig. 8, each heating element may be in the form of a hollow casing having a vertical series of transverse baffles 40 with the alternate ones being staggered so as to provide oppositely arranged openings 41 which serve to define a zig-zag or back and forth flow of the products of combustion from the lowermost portion of the casing to the uppermost portion thereof from whence such products of combustion will discharge through the stack 21 to the atmosphere outside of the building. A damper 31" may be provided in each stack to controllably retard the chamber heating stream of gaseous products in its flow through each heating element and thereby permit a regulated heating of the enameling chamber.

In lieu of the double combustion chambers being arranged beneath the heaters 3, they may be disposed laterally and to one side of the enameling chamber 1, as shown in Figs. 10, 11 and 12, or a single combustion chamber or confined space may be provided for both heating elements, as shown in Figs. 7, 8 and 9. Otherwise, these two modifications are generally identical and therein the fuel jet is indicated by the numeral 17' while the fume conveying passage is indicated by the numeral 22', both leading into the confined space 18' and communicating with the combustion chamber, with the drum extension thereof being indicated by the numeral 42 in Figs. 10, 11 and 12 and by the numeral 43 in Figs. 7, 8 and 9.

The enameling oven is suitably supported on the framework 34' with the lowermost part 3' of each heating element depending beneath the upper level of the framework, in a manner similar to the heaters of the embodiment shown in Figs. 1 through 6. However, in lieu of the combustion chamber discharging upwardly, as in Fig. 1, each combustion chamber is supported above the framework 34' to discharge its products of combustion through lateral connecting passages (43' in Figs. 7, 8 and 9 and 42' in Figs. 10, 11 and 12) into the heating element in a plane above the lowermost or depending part 3' thereof. For concentrating the enamel-baking heat close to the entranceway 7', provision is made to carry the heating and gaseous products of combustion down into such lowermost part 3'. This will bring the peak of the heat curve well down in the enameling chamber and serve to accelerate the enameling process, as has been previously set forth in the description of the initial embodiment. To this end the enameling chamber is supported upon the frame structure 34' between the side uprights or frame members 44 of channel form. A cover plate 45 seats upon each channeled upright 44 to form therewith a vertical flue 46. Each flue communicates with the two heating elements by nipples 47 which are so disposed as to cause the chamber-heating gases to enter the zig-zag heating stream at intervals and in the direction of flow. In other words, the heating stream will enter the lowermost or first pass A, Fig. 8, from the right flue 46 so as to initiate the flow toward the left before passage upwardly through the left pass-connecting opening 41 into the pass B where the nipples from the left flue 46 will discharge further increments of hot gas into the heating stream to thereby urge the flow back toward the right, and again upwardly through the right hand pass-connecting opening 41 into

the next upper or third pass C, at which point the second pair of nipples 47 in the right flue 46 will discharge other increments of the heating fluid into the hot stream, thereby giving added impetus thereto. A special L-shaped nipple 47' will serve to conduct the hot gases into the depending lowermost part 3' through the supporting frame structure 34'. This special nipple provides a bottom opening and constitutes a means for furnishing heat to such depending lowermost portion of the heater in the same manner as the heat supplying connections 20 heretofore described. This special heat supplying means 47', together with the immediately superimposed nipple 47, will constitute a pair of nipples for furnishing the lowermost pass A with the hot products of combustion.

To concentrate the heat in the lowermost portion of the heating element, the special nipple 47', the next superimposed nipple 47, and the lower nipple 47 of pass B all have constant communication with their respective vertical flues 46, while the remaining nipples thereabove will be given permissive and selective communication with the respective flues by valves 48. In certain enameling operations all of the valves 48 may be seated to close their respective nipples 47 so that the heating stream will enter the heating element only through the three constantly opened nipples. Should additional heat be required, the valves may be selectively opened without affecting the concentrated heat application to the freshly coated wire as it enters the baking chamber.

If more heat is desired in the lowermost pass A, one or more additional nipples 47" may be provided in open communication with the respective manifold-forming flue 46. The baffles in the companion heating element, shown by the dotted lines 40, Figs. 8 and 11, may be staggered relative to those in the full line showing and consequently the communicating nipples will be arranged in reverse order. The heating streams of the two elements will therefore flow in opposite directions through the passes to better distribute the enamel baking heat.

In lieu of the heat supplying vertical flues 46, individual gas burners 50 may be provided for supplying the heat. The products of combustion from such burners will enter the respective passes A, B, D, as shown in Fig. 13, with special provision being made in the form of a bottom burner 50' to supply the lowermost portion 3' with the important bake-accelerating heat. This bottom burner, like the other bottom heat-supplying means 20, 47', will act to concentrate the heat application to the zone immediately adjacent the entrance slot 7' to lower the peak of the heat curve down in the lower part of the enameling oven. The gas burners may be of any approved form such as the well known Kemp gas burner, the gas being supplied to these burners by pipe connections. A protecting layer of heat insulating material 6" may be placed upon the bottom wall 6' in which the entrance slot 7' is formed to retain the heat within the enameling chamber.

In a wire enameling process it is very desirable, and imperative for the greatest efficiency, to maintain the enamel bath at a predetermined temperature. It is also highly desirable to maintain a predetermined room temperature so that as the wire strands lift out of the bath the fresh enamel coating will enter the slot 7 in proper condition for the baking process. By reason of

the fact that the enamel fume has been completely disposed of by the burning process above set forth, the stack products of combustion which are still hot may be utilized, in accordance with this invention, to maintain the bath and room atmosphere at the desired temperature. To this end the products of combustion may be conducted from the stack 21 through suitable radiators strategically located in the room, or the stack gas may be passed through a steam boiler 52 for generating steam to be supplied to the radiator 53 by the steam conducting pipes 54. The radiator may be suitably located at proper points on the side wall of the room.

The enameling process and apparatus above set forth is highly efficient in that the fume is completely consumed without any trace appearing in the final discharge of the products of combustion to the outside atmosphere. The restricted induction creates the high fume burning temperature with a minimum consumption of fuel. By burning the fume at this high temperature heretofore wasted energy or B. t. u. is conserved by conducting the hot fume stream from the enameling chamber into the confined space while maintaining the fume stream temperature close to what it was when emerging from the chamber. The employment of the bottom heating means for the heating elements 3 enables the enameling process to be expedited by lowering the peak of the heat curve within the baking chamber and at the same time permits a gradual cooling of the wire above the peak to a safe temperature for emerging from the chamber. And finally the complete burning of the fume enables further conservation of the heat energy in the maintenance of the bath and room temperatures. In addition to the restricted induction which creates the high flame temperature there will also be a freer induction of the fume particles from the fume and air stream throughout the length of the flame. These fume particles are drawn into the flame and therefore in what might be considered a partially completed flame action there will be found four constituents, namely unconsumed fuel gas, air, fume, and the products of combustion, with the first three being eventually consumed and passing off in the oven heating stream of hot combustion products.

The burner nozzle 17 may be suspended or mounted for angular adjustment as well as for adjustment in and out of the throat 25 to enable proper placement of the jet and flame for securing the desired restricted induction. The terms "enamel" and "fume" are herein used in a comprehensive manner to include like industrial operations wherein objectionable fume, dust, and the like, emanate from a processing chamber. In the appended claims the expressions such as "close to one side of such confined space" are to be understood as locating the central axis of the fuel flow or outlet at a sufficient distance from the central axis of the throat 25 to cause a greater induction in one part of the cross sectional area thereof than in other parts thereof, and at the same time, direct the flow of the fuel elements and the flame into the combustion chamber in a manner to maintain them substantially in flow contact with the surface to be heated in contrast to flame impingement. While the foregoing description has been given in detail, it is without thought of limitation since the inventive principles involved are capable of assuming other physical embodiments, and the fume consuming process or method capable of

being practiced with such other physical embodiments, without departing from the spirit of the invention and the scope of the appended claims.

What is claimed is:

5. The method of burning enamel fume, consisting in withdrawing the hot fume from an enameling chamber under its own heat head, conducting the fume stream while hot into a confined space, directing fuel under pressure close to one wall of such confined space to restrict the induction of the fume over such wall and thereby enable the more intense heating of the latter for burning the fume delivered by the induction of the jet in all other parts of said confined space, and controllably admitting additional air into the fume stream for supporting the burning of the fuel and the fume.

20. The method of burning fume, consisting in directing an ignited jet of fuel under pressure into a confined space close to one wall thereof for effecting restricted induction over such wall and free induction in all other parts of the confined space about the jet thereby to cause the jet flame to depress toward and extend along said wall to heat it to an intense heat by reason of the restriction in the amount of the cooling air and fume contact with the wall, and feeding fume into said confined space together with the required volume of combustion supporting air necessary to complete the burning of the fume for such restricted and free induction.

25. The method of burning fume, consisting in discharging an ignited jet of fuel under pressure into a confined space close to one side wall thereof for effecting restricted induction at such side and free induction in all other parts of the confined space about the jet thereby to cause the jet to hug to said side wall and heat it to an intense heat in precluding a cooling contact of the wall by air and fume, feeding a stream of air and fume mixture, as it leaves an enameling chamber, into the confined space for such restricted induction, admitting additional air into the stream sufficient to support the fuel combustion and the fume consumption by the flame, utilizing the products of the fuel and fume combustion to supply heat for the enameling chamber, and controlling the rate of flow of the combustion products through the enameling chamber to regulate the enamel baking temperature while precluding a pull upon the mixture of an induction disturbing nature.

30. A wire enameling furnace comprising an enamel baking chamber having a wire entrance and a wire exit through which latter the wire leaves the chamber with an air diluted fume stream, a heating element arranged for heating the chamber, a confined combustion space connected to the heating element for delivering the hot gases of combustion into the heating element for rendering the same operative, a fuel nozzle delivering a jet of fuel into the confined space closer to one wall thereof for obtaining a restricted induction along the wall by the jet and free induction elsewhere about the jet thereby to cause the jet flame to hug the wall for heating the same more intensely for fume burning, and means for directing a flow of the fume stream from the exit opening into the confined space.

35. The method of supplying and burning enameling oven fume, consisting in directing a jet of ignited fuel into a confined space, supplying a mixture of air and fume to such space,

controlling the volume of air so supplied substantially to that required to complete the combustion of the fuel and the fume only, holding the jet flame close to one wall of the confined space to restrict the jet induction of the mixture over such wall, regulating the inclination of the jet flame toward such wall to lay the flame substantially upon the wall to heat the same to a fume-burning temperature, and leaving the jet effective more freely on the mixture elsewhere in such confined space to supply the combustion supporting air to the fuel and fume exposed in said other parts of the confined space.

6. The method of burning enameling oven fume, consisting in introducing fume from an oven along with added air into a confined space, then directing an ignited jet of fuel close to and inclining toward one wall of such confined space for restricting the induction of air and fume over such wall to lay the flame along the wall to heat the same, and feeding into the flame by the freer induction elsewhere about the jet the air and fume from all other parts of such confined space.

7. The method of burning enameling oven fume, consisting in introducing fume and combustion-supporting air into a confined space, directing a jet of fuel into such space close to one wall thereof and at an incline theretoward to restrict the induction of the fume and air mixture over such wall to lay the jet flame thereon for raising the flame temperature to approximately that of the theoretic flame temperature, and more freely inducing the air and fume from elsewhere about the jet for feeding the fume into the effective intensified flame and for supplying the air to support the burning of both the fume and the fuel.

8. The method of burning enameling oven fume, consisting in introducing fume and combustion-supporting air into a confined space, directing a jet of fuel into such space close to one wall thereof and at an incline theretoward to restrict the induction of the fume and air mixture over such wall to lay the jet flame thereon for raising the flame temperature to approximately that of the theoretic flame temperature, more freely inducing the air and fume from elsewhere about the jet for feeding the fume into the effective intensified flame and for supplying the air to support the burning of both the fume and the fuel, and finally in utilizing the products of the completed combustion cooled to an oven energizing temperature for supplying the required operative heat to the enameling oven.

9. The method of operating an enameling oven having an enameling chamber with a heating radiator therein; consisting in introducing fume and air into a confined space with the volume of air being predetermined to support combustion of both fuel and fume substantially without excess; directing a jet of ignited fuel, positioned close to one wall of such confined space, to restrict the induction of such air and fume over the wall for layering the jet and flame thereonto to intensify the flame temperature; and feeding the air and fume content from all other parts of such confined space into the flame for supplying the combustion-supporting air for the burning of both the fuel and the fume and finally flowing the products of combustion into the heating radiator for rendering the oven operative.

10. The method of burning fume, consisting in directing an ignited jet of fuel under a predetermined pressure into a confined space close to

one wall thereof for effecting restricted induction thereat and freer induction in all other parts of the confined space about the jet to cause the jet flame to hug said wall and in doing so to approach more nearly the theoretic flame temperature sufficient to burn fume, feeding the fume stream flowing hot from an enameling chamber into the confined space to be so induced by the jet, adding air to the fume after it leaves the enameling chamber and in volume sufficient to support the combustion of both the fuel and the fume, and in limiting the volume of the added air substantially to the theoretical air required for such combustion thereby to maintain the fume burning temperature.

11. The method of burning fume, consisting in discharging an ignited jet of fuel under pressure into a confined fume-holding space close to one wall thereof for effecting restricted induction of fume along such wall and freer induction in all other parts of the confined space about the jet, in directing the jet angularly toward the wall to cause the restricted induction to attract the flame toward the wall while moving therealong for shielding the wall from the cooling influence of the fume content of the freer induction, conducting a fume stream from a fume generator into the confined space for such induction, flowing a predetermined volume of additional air into the fume stream sufficient to support the fuel combustion and the fume consumption by the flame, and in controlling the volume of added air by observing the flame characteristic.

12. The method of operating an enameling oven, consisting in directing an ignited jet of fuel under pressure into a confined fume-holding space close to one wall thereof for effecting a restricted induction along such wall to preclude any substantial cooling contact of the fume elsewhere about the jet therewith and a freer induction in all other parts of the confined space about the jet, in inclining the jet to cause its flame to hug said wall while moving therealong to enable the generation of a fume burning temperature, in feeding a stream of fume mixture from an enameling chamber into the confined space for such restricted and free inductions, in adding a theoretic volume of air into the fume stream sufficient to support the fuel combustion and the fume consumption by the flame moving along the wall, and utilizing a portion of the heat of the fuel and fume combustion to supply the heat required for operating the enameling chamber.

13. A wire enameling oven having a baking chamber with an entrance slot through which the wire and air is admitted to the chamber and an exit slot through which the wire and the hot air-mixed fume stream pass from the chamber, a fume collecting compartment into which the exit slot opens, a combustion chamber, a heating element arranged to heat the baking chamber and connected to receive the products of combustion from the combustion chamber for rendering the heating element effective, means for delivering the hot fume stream from the collecting compartment into the combustion chamber for being consumed therein, and fuel burner nozzle means directed into the combustion chamber close to one wall thereof and inclined relative to the wall for restricting the fume induction along the wall and freer induction elsewhere about the nozzle means, and controllable means for admitting additional air to the fume stream for the burning of the fume.

14. A wire enameling oven having a baking

chamber with an entrance slot through which the wire and air is admitted to the chamber and an exit slot through which the wire and air-mixed fume stream pass from the chamber, a fume collecting compartment into which the exit slot opens, a combustion chamber connected for heating the baking chamber, means for conducting the fume stream from the collecting compartment into the combustion chamber for being consumed therein, burner nozzle means arranged to direct fuel into the combustion chamber close to one wall thereof and inclined toward the wall for effecting restricted induction along the wall to hold the fuel and flame on the wall while admitting freer induction of the fume content elsewhere about the nozzle means, metering means admitting the necessary combustion supporting air into the fume stream, and means operable for mechanically maintaining the flow of the fume stream from the collecting compartment to the combustion chamber.

15. A wire enameling oven having a baking chamber with an entrance slot through which the wire and air is admitted to the chamber and an exit slot through which the wire and air-mixed fume stream pass from the chamber, a compartment into which the exit slot opens for receiving the hot fume stream under its own heat head, a combustion chamber, means for delivering the hot fume stream from the compartment into the combustion chamber for being consumed therein, means for adding air to the fume stream as it leaves the compartment for supporting its combustion, a burner nozzle directed into the combustion chamber closer to one wall portion thereof for laying the nozzle jet and flame on the wall portion to restrict the induction of the fume and air flow thereover relative to the freer induction of the fume and air flow elsewhere about the jet and flame, a stack for conducting away the products of combustion, and damper controlled means arranged to regulate the rate of the fume air flow from the compartment for maintaining the heat head movement of the hot fume stream from the baking chamber substantially constant.

16. A wire enameling oven having a baking chamber with an entrance slot through which the wire and air is admitted to the chamber and an exit slot through which the wire and air-mixed fume stream pass from the chamber, a compartment into which the exit slot opens for receiving the hot fume stream under its own heat head, a combustion chamber connected to have its products of combustion operatively heat the baking chamber, means for delivering the hot fume stream from the compartment into the combustion chamber for being consumed therein, an air inlet in the compartment for admitting combustion supporting air into the fume stream therein, a burner nozzle directed into the combustion chamber closer to one wall portion thereof for laying a fuel jet and flame on the wall portion to restrict the induction of the fume and air flow thereover relative to the freer induction of the fume and air flow elsewhere about the nozzle, means mechanically maintaining the fume and air flow from the compartment to the combustion chamber, and damper means controlling the action of said flow maintaining means to maintain the movement of the fume stream from the baking chamber into the compartment under its own heat head.

17. A wire enameling oven having a baking

chamber with an entrance slot through which the wire and air is admitted to the chamber and an exit slot through which the wire and air-mixed fume stream pass from the chamber, a compartment into which the exit slot opens for receiving the hot fume stream under its own heat head, means for adding combustion supporting air to the hot fume in the compartment, a combustion chamber, a heating element arranged to heat the baking chamber and connected to receive the products of combustion from the combustion chamber for rendering the heating element effective, means for effecting a flow of the fume and air mixture from the compartment into the combustion chamber for being consumed therein, a burner nozzle directed into the combustion chamber closer to one wall portion thereof for laying a fuel jet and flame on the wall portion to restrict the induction of the mixture thereover relative to the freer induction elsewhere about the jet and flame, means mechanically maintaining the flow of the mixture from the compartment to the combustion chamber, damper means controlling the action of said flow maintaining means against substantial disruption of the heat head flow, and means for retarding the flow of the hot products of combustion through the heating element before discharge therefrom.

18. A wire enameling oven having a baking chamber with an entrance slot through which the wire and air is admitted to the chamber and an exit slot through which the wire and air-mixed fume stream pass from the chamber, a compartment into which the exit slot opens for receiving the hot fume stream under its own heat head, means adding combustion supporting air to the hot fume as it leaves the compartment, a combustion chamber, a heating element arranged to heat the baking chamber and connected to receive the products of combustion from the combustion chamber for rendering the heating element effective, means for conducting the fume and air mixture from the compartment into the combustion chamber for being consumed therein, a burner nozzle directed into the combustion chamber closer to one wall portion thereof for effecting restricted induction thereover relative to freer induction elsewhere about the nozzle to lay a fuel jet and flame along the wall portion, and means for regulating the heating of the baking chamber by controlling the flow of the mixture as conducted from the compartment.

19. A wire enameling oven having an upright enameling chamber with a wire entrance slot in its bottom wall and a wire exit slot in its top wall and through which latter an air-diluted fume stream emerges, a hood receiving the emerging fume stream, means for admitting combustion supporting air to the fume stream, a confined space connected to the hood and having a burner nozzle therein disposed closer to one wall portion thereof for restricted induction and directed to cause the fuel jet and flame to hug such wall portion for intensifying the heat to a fume burning temperature in the presence of the fume mixture induced freely elsewhere about the nozzle, a heater for the enameling chamber, and means carrying the products of combustion from the flame into the lowermost portion of the enameling chamber for heating the latter.

20. An enameling furnace comprising an en-

amel baking chamber having an entranceway to admit the wire thereinto with a fume diluting amount of air and an exit opening through which the wire leaves the chamber with a diluted fume stream, a heating element arranged for heating the chamber, a confined fume holding space embodying a combustion chamber connected to the heating element for delivering the hot gases of combustion to the heating element for operating the same, fuel nozzle means delivering a jet of fuel into the confined space close to one wall thereof whereby to restrict the induction of fume thereover and thereby cause the jet flame to extend upon the wall for heating the same to the exclusion of the cooling influence by contact with the fume stream of free induction in all other parts of the confined space, means for directing a flow of the fume stream while hot from the exit opening directly into the confined space for being so induced into the flame, and means for admitting combustion supporting air into the fume stream for flow therewith into the confined space.

MARCUS C. STEESE.
